ABSTRACT

A rotary energy converter embodied as a continuous combustion motor wherein the combustion process or heat-energy supply is external to the internal power producing chamber and rotors. A sealed internal power producing chamber is provided with a high heat latency fluid which can absorb heat energy and transform it into rotary motion through a central rotor and two peripheral rotors.

ENGINE POWERED FROM EXTERNAL ENERGY FORCE

This is a division of application Ser. No. 281,645 filed Aug. 18, 1972.

CROSS REFERENCES TO RELATED APPLICATIONS

The present invention and application is related to my previous U.S. Pat. Nos. 3,463,128 entitled "Rotary Engine" and 3,640,252 entitled "Rotary Internal Combustion Engine." Reference to said U.S. Pat. No. 3,640,252, and especially the drawings thereof, will be most helpful in understanding the developments of the present invention and said patent is deemed included herein by reference.

BACKGROUND OF THE INVENTION

Many different types of rotary energy converters exist in the prior art, and many of these present significant advantages over the reciprocating piston-cylinder type engines currently in use for the automobile engine, for air compressors, motor-generators, and various other applications.

Although the Wankel engine has now begun to achieve some prominence as a replacement for the piston-cylinder type engine, in automobiles and other applications, it was conceived in an era when our presently acute awareness of the air pollution problem had not yet developed to its present awareness. This could also be said of my earlier U.S. Pat. No. 3,463,128.

While the Wankel engine has been recognized as only an interim solution to the problem of air pollution since it also requires afterburners and catalytic converters, it would seem that much more improvement is required in the near future in order to handle the now-critical air environmental problem. My recent U.S. Pat. No. 3,640,252 was a step in that direction since it provided for recycling of burned gases for improved vaporization of fuel and damping of the combustion process for reduction of nitrous oxides. It also provided for the elimination of burning oil in the engine and for mixing fresh air with exhaust gases without external accessories.

My further research into the environmental problem in relation to engines and other energy-mechanical motion converters have led to greater and more significant improvements in rotating abutment-type rotary energy converters.

My analysis and work in the conversion of mechanical energy to useful fluid pressure, and the conversion of energy in the form of fluid pressure to useful mechanical energy (and including the case of internal combustion) have brought forth optimized elements and configurations which most satisfactorily handle the conversion of energy into different forms using the principle of rotary and interleaving abutments.

SUMMARY OF THE INVENTION

The present invention involves an optimal arrangement of rotating and interleaving abutments most easily adaptable to fluid-mechanical and mechanical-fluid energy conversion including the case of combusting fluids. A basic configuration of chambers and internal rotating hubs with abutments is provided such that adjacent rotating elements interleave to form sealed function-chambers permitting entrapment and release of

fluids while at the same time the rotating elements are connected to maintain a timed relationship which also transmits forces.

Three embodiments are used to show the applicability to compressors (mechanical-fluid energy conversion), to a compressed air driven motor (fluid-mechanical energy conversion), and to an internal combustion engine (mechanical to fluid and fluid to mechanical energy conversion).

10 The elements and configuration provided in these rotary energy converters provide simplicity, versatility, and high efficiency, with a variety of advantages when used in the various embodiments.

In the present invention, as in my U.S. Pat. No. 15 3,640,252, precisely formed non-circular curve faces are not required on the arcuate faces of the piston-abutments and valving-abutments. I have found that the ideal motion traced by a rotating piston-abutment around a valving-rotor abutment is described by a prolate epicycloidal curve which then can be circularly approximated since a liberal running clearance is permitted between the faces of adjacent rotors in lieu of gear accuracy and backlash allowances. Excellent sealing is provided and does not require precise angular relationships since each rotor and its abutments is sealed by juxtaposition to the chamber walls as explained in my U.S. Pat. No. 3,640,242.

15 The present invention is set up to use a casing having chambers wherein rotary elements (rotors having extended protrusions or abutments) which interleave to form sealed function-chambers which entrap and release fluids and which provide rotary mechanical motion. The abutments or may also be called lobes such that the head or periphery of each piston-lobe or abutment runs close to the hub of the adjacent rotor in such manner that sealing between the two rotors is achieved without dependence upon precise angular relationships, and each of the rotors in turn alternately provides sealing between its peripheral-head and the hub of the adjacent rotor.

20 One embodiment has the central rotor pistons supported by a disc and wherein the abutments are of the lobe type and the head-periphery of the pistons is sealed against the hub of the abutment valving rotor while also the head-periphery of the abutments is sealed against the stator or casing walls.

25 Thus in each of the embodiments, sealing is provided between rotors and case or between rotors without the need for precision gearing or precise computer-derived curves, so that great versatility can be realized in applying the invention to varied uses.

30 When the invention is applied as a compressor for gaseous media or fluids, it provides a unique feature of regenerative compression for high output pressures in a single stage of compression by recycling part of the compressed gases back into the compression function-channel of the next succeeding compression phase of the compressor. The actual weight of the charge thus fed back is proportional to the pressure head against which the compressor is working; therefore a positive feedback is provided around the normal volumetric compression ratio of the compressor such that the power available to drive the compressor and the relative leakage at a given speed will limit the head pressure that can be achieved by this compressor.

35 When applied as a vacuum pump, a relatively high vacuum can be achieved in a single pumping action.

When a plurality of these pumps are cascaded, a further increase in vacuum pumping action can be realized.

When applied as a utilizer for converting gas or fluid pressure to rotary mechanical motion, the symmetrical embodiment of the invention provides reversible rotary action with no dead-center effect since the abutment valving rotor as well as the piston rotor contributes to the the output torque through a part of each rotation of the rotors. Reversing the direction of the gas or fluid flow, or interchanging the inlet and outlet ports gives reversible rotation of the output shaft. Output can be taken off any or all of the rotor shafts since some of the power is contributed by each rotor. The central piston rotor, however, will normally be used as the output power rotor since its output is greater than each of the valving abutment rotors.

By using the embodiments of the compressor and utilizer with a combustion chamber having fuel injection and ignition means, there is provided an embodiment of a continuous combustion engine. In this simple and basic embodiment all of the desirable features of my U.S. Pat. No. 3,640,252 are retained together with the improvements provided by the present invention which includes: greater simplicity and efficiency, larger displacement for a given rotor diameter, a virtually constant pressure continuous combustion cycle which is significantly preferable to a pulsating on-off type of combustion cycle, and adaptability to the use of high temperature, high strength ceramic material for the rotors and casing capable of reducing the loss of heat energy which loss is characteristic of metallic type rotor and stator construction.

BRIEF DESCRIPTION OF THE DRAWINGS

The present invention will be more adequately understood by reference to the following drawings which accompany the attached specification and wherein:

FIG. 1A is an embodiment of the invention when used as a dual regenerative compressor and shows a top view of the interior mechanism; FIG. 1B is a view in elevation of a central cut taken through the compressor;

FIG. 2A is an embodiment of a dual symmetrical utilizer showing a top view of the interior mechanism; FIG. 2B is a view in elevation of a central cut taken through the utilizer;

FIG. 3A is an embodiment of a continuous combustion engine and shows a top view of the interior; FIG. 3B is a view in elevation of a central cut taken through the engine.

FIG. 4A is a diagram showing a valving rotor abutment cavity used as a stationary reference for the motion of a piston-abutment interleavingly moving about it to describe the curve of a prolate epicycloidal trace; FIG. 4B is a diagram showing more detail in the cooperative interleaving as between the piston rotor and the abutment valving rotor.

FIG. 5A is a drawing of an embodiment of a continuous combustion engine with ram intake; FIG. 5B shows the fuel-injector igniter which can be used in the combustion chamber of this and other embodiments.

FIG. 6 is a drawing showing an embodiment of the invention as a continuous combustion engine with high pressure cooling.

FIG. 7 is a drawing showing a continuous combustion engine with arrangements for cooling and heat redistribution.

FIG. 8 is a drawing of an external combustion engine with a sealed internal fluid for power generation.

DESCRIPTION OF COMPRESSOR EMBODIMENT

As will be seen in FIG. 1A an embodiment of the dual regenerative compressor is shown with an enclosing casing 20. Within the casing are three circular and annular chambers which may be designated as a central chamber 38, a first peripheral chamber 76, and a second peripheral chamber 75. The central chamber 38 is seen having common-chamber areas 62 and 61 with the first peripheral chamber 76 and the second peripheral chamber 75 respectively. Within the three chambers are provided three abutment rotors, the central rotor 2, the first peripheral valving rotor 40, and the second peripheral valving rotor 24.

Fluids are taken in through intake ports 60_i and 60_{i'}. Exhaust fluids are vented through exhaust ports 60_e and 60_{e'}.

The central rotor 2 is mounted on a shaft 12 by means of two rotor discs 2_{z1} and 2_{z2} shown in FIG. 1B, to which are attached three piston-abutments shown as 2_a, 2_b, and 2_c. Referring (FIG. 1A) to piston-abutment 2_c, it will be seen that the piston-abutment has a convex leading face 2L, a convex trailing face 2_t, and a head surface (periphery) marked as 2_h. The arcs of 2L and 2_t follow the sides of a circle whose center is shown at point M.

The stationary core or disc 3 has two cutouts shown on opposite sides which have a concave face and are designated 3L and 3_r.

The central chamber 38 has an upper section 38_c and a lower section 38_e wherein fluids are trapped between the two piston abutments (function-channels) as they rotate past the casing 20.

The first peripheral valving rotor 40 is seen having three abutments or protrusions 40_a, 40_b, and 40_c which rotate around a stationary core or disc 42 which is mounted around shaft 47. Referring to valving abutments 40_a and 40_b, it will be seen that the abutment side faces are concave and have a leading edge or face 40L and a trailing face 40_t. The head or peripheral arc 45 of the abutment is convex and designated as the head 40_h. The concave arcs of the side faces of the abutments follow an arc of a circle whose center is shown at C₁.

Likewise the second peripheral valving rotor 24 has three abutments 24_a, 24_b, and 24_c having leading edges or faces 24L, trailing faces 24_t, and head area 24_h. The rotor 24 has a stationary core or disc 26 around shaft 28. A cutout 24_m is provided on core 26 for clearing of the rotating head face area 2_h which interleaves with the peripheral rotor abutments during rotation. The side faces of the abutments are concave and follow the arc of a circle whose center is shown at C₂.

The intake ports 60_i and 60_{i'} are provided with an expanding throat shown at 60_a and 60_b where the casing is rounded off to provide the throat area.

The exhaust ports 60_e and 60_{e'} have formed within them a channel with lips 20_e and 20_{e'} juxtaposing the head areas 40_h and 24_h of the peripheral abutments.

FIG. 1B shows in elevation a central cut through FIG. 1A. The central rotor 2 is mounted on shaft 12 having an output shaft portion 12_a. The main shaft 12 is supported by bearings 5 and 6.

The first peripheral rotor 40 which comprises discs 40_{z1}, 4_{z2}, and lobes 40_a, 40_b, and 40_c is attached to shaft 47 which is held by bearings 44_a and 49.

The second peripheral rotor 24 which comprise discs 24_{z1}, 24_{z2}, and lobes 24_a, 24_b, and 24_c is fastened to shaft 28 which is supported by bearings 29_a and 33.

Each of the rotors 40, 2, and 24 has a stationary central core, or disc 42, 3_a, and 26 respectively, about which each respective rotor rotates.

As further seen in FIG. 1B, the central rotor 2 is attached to upper and lower carrier discs marked 2_{z1} and 2_{z2}. The first peripheral rotor likewise has carrier discs 40_{z1} and 40_{z2}, and the second peripheral rotor 24 has upper and lower carrier discs 24_{z1} and 24_{z2}. All of these carrier discs rotate with their respective rotors and are considered part of the respective rotors.

Reference may be made to my U.S. Pat. No. 3,640,252 and especially to the exploded view of FIG. 3 thereon for a greater visualization of the above elements.

Central chamber 38 is shown occupied by rotor 2 while chamber 76 is occupied by rotor 40 and chamber 75 is occupied by rotor 24. Shaft 12 of rotor 2 is fastened to a gear 8 while shaft 47 of rotor 40 is fastened to gear 50, and shaft 28 of rotor 24 is fastened to gear 34. The three gears 8, 50, and 34 are interconnected as shown in FIG. 1B.

Each of these gears has a gear pitch line within the gear teeth, which pitch line is marked 50_p, 8_p, and 34_p respectively, in FIG. 1B.

Power or torque, when applied to shaft 12_a will operate the rotors for delivery of compressive work on fluids or for provision of a useful vacuum, depending on the use made of the intake and exhaust ports.

Compressor Operation

Air, gas, or other fluid is applied to intake ports 60_i and 60_{i'} for intake into the first peripheral chamber 75 and the second peripheral chamber 76. For simplification of explanation, the fluid may be regarded as entering intake port 60_i. Torque or mechanical motion is applied to shaft 12_a causing the rotation of rotors 2, 40, and 24. The incoming fluids are pushed into the 38_c portion of chamber 38 by the piston abutments 2_a, 2_b, and 2_c and the peripheral valving rotor abutments 40_a, 40_b, and 40_c, which operate in interleaving fashion with 2_a, 2_b, and 2_c. The fluid is then forced through chamber portion 38_c where it is compressed between the head 2_h of, for example, abutment 2_b and the concave surfaces of peripheral abutments 24_a and 24_c. As the rotation of rotor 24 and rotor 3 proceeds, the fluids are further moved by the abutments of rotor 24 around to the exhaust port 60_e' where they are forced into a compressed gas tank.

Likewise, the rotation of the main rotor 2 pushes fluids through chamber portion 38_e out to the other exhaust port 60_e (which may be made common to exhaust port 60_e') to the compressed fluids tank. Furthermore, rotating motion of the abutments of rotor 40 also carrier intake air from port 60_i over to exhaust port 60_e to add further pumping action to the output.

The operation of this embodiment for the compression of fluids is in some respects similar to the compression phase of internal combustion engines of the rotating abutment type as exemplified in my U.S. Pat. No. 3,640,252 and others. The present invention and the embodiment is, however, considerably more advanta-

geous in that regenerative feedback of some of the compressed fluids into the next succeeding compression phase is deliberately facilitated, whereas in the prior art, including my U.S. Pat. No. 3,640,252, the regenerative effect was minimized or not used at all.

As a result of continued research in rotating abutment type energy converters, I have discovered that a very beneficial result can be achieved by allowing some of the compressed fluids or charge from each compression phase which is unavoidably trapped between the leading edge of each abutment and the head of each piston as it begins to pass between two adjacent abutments in the common chamber areas 61 and 62. The extra fluid that is fed back adds to the total volume of fluid that is trapped between two adjacent pistons at the beginning of each successive compression phase, thus increasing the initial pressure of the charge trapped between two pistons to a valve above atmospheric pressure.

Taking a series of successive compression phases which occur during rotation of the abutments due to externally applied torque and considering the case where the compressor is pumping against a head pressure, the regenerative compression effect becomes cumulative so that the amount of air or fluids trapped between the pistons is increased as the head pressure increases.

If the volumetric ratio (the ratio of the volume of space between adjacent pistons to the volume of the space at the end of a compression phase just before the exhaust port closes) is, for instance 8:1 and the total weight of fluid charge between the pistons is 10 milligrams of air (or gas) at atmospheric pressure, the fluid trapped in the end space at the end of a stroke (such as the space between abutments 24_b and 24_c) will be 1.25 milligrams with no head pressure (other than 1 atmosphere) against the exhaust (outlet) port 60_e' of the compressor. This 1.25 milligrams will be fed back so that 11.25 milligrams of air (or other fluid) will be trapped between the next pair of pistons (as between 2_b and 2_c of rotor 2).

If, however, the head pressure increased to 2 atmospheres by continuation of the action of the compressor, then this same "end space" at the end of each compression cycle, would be entrapping 2.50 milligrams of air or fluid and feeding it back between the next interleaving pair of pistons so that 12.50 milligrams of air or fluid would be entrapped therebetween.

Again, if the compressing action continues until the head pressure increased to 4 atmospheres, the "end space" would contain 5.00 milligrams of air, and 15.0 milligrams of air or fluid would be trapped between the next oncoming pair of pistons.

At 8 atmospheres of head pressure, the "end space" would contain 10.00 milligrams of air or fluid, and the next oncoming pair of pistons would entrap 20.00 milligrams of air or fluid.

If some of the air or fluid being compressed is also at the same time being utilized or released to do work, but at the same time the head pressure is kept at 8 atmospheres, then 10.00 milligrams of air or fluid would be fed back to maintain the value of 20.00 milligrams of air entrapped between each pair of pistons; and thus 10.00 milligrams will be available as a useful output. This is stated under the ideal conditions of isothermal compression and zero leakage.

But it should be understood that, assuming these same ideal conditions, a reciprocating piston-cylinder type compressor with a corresponding volumetric ratio of 8:1 would retain the full charge within the cylinder at 8 atmospheres of head pressure, and the available output would be zero because all of the air (or gas or fluid) would be re-expanded within the cylinder and no fresh charge would be being taken in.

Obviously there would be some losses in an actual situation with a practical compressor under actual operating conditions. However, the advantages of the regenerative feedback can be readily seen through this idealized example.

At relatively high operating speeds, where relative leakage is low, this type of regenerative rotary compressor offers steady output of high pressure capability with a high delivery efficiency, whereas a reciprocating piston-cylinder type compressor suffers diminished delivery as the head pressure becomes higher in value.

The rotary compressor embodiment of this invention also offers the important advantage that glass, ceramics, plastic, and other non-corroding material can be used in its construction since there is no frictional or contacting surfaces within the compressor channels. Additionally, the output is free from pollution by lubricating oil and its carbon-sludge by-products.

Furthermore, the above described embodiment is equally useful as a vacuum pump which is relatively free from pulsation at the intake. The operative use as a vacuum pump is similar in operation to the operative description above except that the regenerative feature has little effect where no head pressure is encountered.

Description of Utilizer Embodiment

In the embodiment of the invention, designated as a "Symmetrical Utilizer," wherein gas, vapor or other fluid pressure may be used to produce mechanical motion output such as usable torque on an output shaft, reference is now made to FIG. 2A. It will be seen that the elements of FIG. 2A basically follow the same configuration and parts as described under the description for FIG. 1A. However, a few differences must be noted and explained.

It will be seen that whereas the exhaust or outlet ports 60_e and $60_{e'}$ of FIG. 1A have extended lips 20_e and $20_{e'}$, this is not true of the Utilizer embodiment of FIG. 2A where the throat of the ports are symmetrically widened as seen at 20_u and $20_{u'}$. Further, where the compressor of FIG. 1A has stationary discs 42 and 26 within the first and second peripheral rotors, the Utilizer of FIG. 2A has rotors 40 and 24 made of integral hubs 40_u and 24_u integral with the abutments of the rotors.

As with the compressor, the Utilizer of FIG. 2A has a central shaft 12, and first and second shafts 47 and 28 which connect respectively to gears 8, 50, and 34. And similarly to the compressor of FIG. 1A, the gears of FIG. 2A are interconnected one with the other to maintain the timed relationship of all three rotors.

Similarly to the compressor, the Utilizer of FIG. 2A has points designated M, C1 and C2 which are the centers of circles having arcs which define the shape of the piston and the valving abutment side faces. Also as in FIG. 1A, the Utilizer of FIG. 2A has a stationary disc or core 3_a having arcuate cut-outs 3L and 3r.

As will be seen in the elevated view of the Symmetrical Utilizer of FIG. 2B, the casing 20 supports the cen-

tral rotor 2 on shaft 12 by means of bearings 5 and 6. Peripheral rotor 40 on shaft 47 is supported by bearings 44a and 49 while rotor 24 is held by bearings 29a and 33.

The main rotor shaft 12 of rotor 2 is fixedly connected to timing gear 8 while rotors 40 and 24 are also fixedly connected to gear 50 and 34 through their respective shafts 47 and 28. Two rotating carrier discs 2_{21} and 2_{22} are integral with the rotor 2 of FIG. 2B as in FIG 1B. The Utilizer of FIG. 2B also has a stationary core or disc 3_a with the rotor 2 rotating about it.

The shaft 12 of the central rotor 2 has an extension portion marked 12_a from which output power or torque may be derived.

Utilizer Operation

With the application of compressed air or other fluids to the inlet ports 60_i and $60_{i'}$, the first peripheral rotor 40 is forced to turn counterclockwise, the rotor 2 is turned clockwise, and the second peripheral rotor 24 is turned counterclockwise. During the course of this rotation, the intaken fluids are trapped between the pistons of rotor 2 and carried past channels 38_c and $38_{c'}$ to be exhausted at outlet ports 60_e and $60_{e'}$. Likewise, rotor 40 traps the incoming fluids and carries them through chamber 76 to exhaust at outlet port 60_e while at the same time rotor 24 takes incoming fluid through inlet port $60_{i'}$ through chamber 75 to be exhausted at outlet port $60_{e'}$.

The action of the intaken compressed fluids or gases causes rotation of all three rotors which are linked together through gears 8, 50, and 34 to provide a continuous torque on the output shaft 12_a from whence useful mechanical motion may be derived.

Referring again to FIG. 2A, it will be seen that the utilizer is similar to the compressor except that the inlet ports 60_i and $60_{i'}$ and the outlet ports 60_e and $60_{e'}$ are common to both rotors in the common-chamber areas 62 and 61, where the central chamber 38 overlaps with the peripheral chambers 76 and 75.

The symmetrical configuration of the utilizer permits the inlet and outlet ports to be interchanged for purposes of application of the driving fluid so as to cause reversal of rotation of each of the rotors thus providing a torque output on shaft 12_a in a reverse direction than previously.

There is no dead center effect in any position of the rotors since the peripheral valving abutment rotors as well as the central piston abutment rotor all contribute to the output torque. If an odd number of piston-abutments are used in the central rotor and the two peripheral abutment rotors are oriented 180° apart (as shown in FIG. 2A), then the compressed fluid flow intake (and output torque) is very smooth since the end of a stroke on one peripheral rotor corresponds to the middle of a stroke on the other peripheral rotor.

The inlet ports on the two opposite sides of the Utilizer can be connected in common through an external ducting means, and the same may be done with the two outlet ports in order to make them common.

Description of Continuous Combustion Engine

Referring to FIG. 3A which is an embodiment of the invention used as a basic continuous combustion engine, it will be seen that the previously described principles of the compressor and the utilizer are combined with a continuous combustion chamber to provide a

constant pressure type internal combustion engine. Herein, considerable advantages are provided over my U.S. Pat. No. 3,640,252 and other prior art rotating abutment type engines all of which have a pulsating effect in the combustion process, while my present invention provides a smooth continuous combustion power effect.

Helpful reference may be had to my U.S. Pat. No. 3,640,252 wherein the exploded view of FIG. 3 of that patent will help in visualizing the overall configuration and where, in so far as possible, I have carried forth herein the same numbered elements as closely as is possible.

In FIG. 3A, a casing 20 is provided with a central chamber 38, and first and second peripheral chambers 76 and 75, and wherein there are common chamber area 62 and 61. A central rotor 2 rotates in the central chamber 38 while peripheral rotors 40 and 24 rotate in chambers 76 and 75 respectively. An intake or inlet port 60 admits fluids while an exhaust or outlet port 72 is used for venting of used fluids. The throat or side faces of inlet port 60 has enlarged walls at 60_a and 60_b.

The central chamber 38 has an upper portion 38_c which compresses intaken fluids and a lower portion 38_e wherein combusted fluids are expanded and removed to the exhaust port 72.

The central rotor 2 has a central shaft 12 on which is built a hub 2_u from which extend four pistons or lobes marked 2_a, 2_b, 2_c, and 2_d. Each piston has a head area 2_h and side faces, one of which is the leading face 2L and the other is trailing face 2_t. These leading and trailing faces form the arcs of a circle whose center point is designated M. The pistons may also be described as piston-abutments or piston lobes. The central rotor 2 has a hollow area within it which are outlined by the line 2L_o.

The periphery of the hub 2_u is labelled 2_p, and an arrow shown upon the hub designates a clockwise rotation.

The first peripheral rotor or valving rotor 40 has three abutments 40_a, 40_b, and 40_c protruding from hub 40_u whose periphery is marked 40_p. The hub and abutments rotate on shaft 47 in the peripheral chamber 76 in the counterclockwise direction shown by the arrow. The line 40L_o marked the internal hollow area of rotor 40. The side faces of the abutments follow an arc of a circle having its center at point C₁.

The second peripheral rotor 24 operates in peripheral chamber 75 and has three abutments 24_a, 24_b, 24_c extending from hub 24_u having a hub periphery 24_p, the entire rotor being mounted on shaft 28. The outline of internal hollows of the rotor is marked by line 24L_o. The side faces of the peripheral rotor abutments form arcs of a circle whose center is designated at point C₂.

The second peripheral chamber 75 is made with an internal arcuate barrier wall 75_b which forms an internal channel 68, between the lower and upper portions of chamber 75 in addition to sealing the cavity 75_a between the faces of the abutments of the second peripheral rotor. The lower portion of the chamber 75 serves as an ignition-combustion area 68 and is provided with an ignition means 69 and fuel injector 69_i which delivers fuel vapor to the combustion chamber.

The common-chamber area are shown at 61 and 62, and the casing 20 may be provided with fins 21 for extra cooling purposes.

In FIG. 3B is shown a side or elevation view of FIG. 3A wherein a casing 20 houses the central chamber and the two peripheral chambers holding the rotors 2, 40, and 24.

5 The central rotor is hollowed out along the line 2L_o with the abutments shown hatched solidly at 2_d and 2_c. The central rotor shaft 12 has an output shaft portion 12_a and the central rotor 2 is held by a top bearing 5, a lower bearing 6 while the end portion 12_a has a seal 10 4. Attached to the rotor shaft 12 is a timing gear 8 having a gear pitch line 8_p. The top part of shaft 12 has a hole or opening 16_a permitting cooling air to enter the piston interior 16_b where it may exit through hole 16_c and 16_d into an open area 16_e.

15 The casing 20 may have cooling air intake ports 17_a to bring air circulation into the interior of the engine. A centrifugal blower fixedly attached to shaft 12 draws cooling air from the interior of the rotors by way of open areas 16_e and 16_f and exhausts it out through an outlet in case 20 (not shown).

20 The first peripheral rotor 40 is shown held in place by bearings 44_a and 49 through its shaft 47. The interior hollow of rotor 40 is lined by line 40L_o. Cooling air intaken into area 17_b may enter port 17_c into the rotor 25 interior and pass out through port 17_d into area 17_e where it may circulate around shaft 47 through passage 17_f into passage 16_f. The hatched area of rotor 40 shows the abutment 40_a while the opposite side of this first peripheral rotor has piston 2_d interleaved between 30 abutments 40_b and 40_c (not shown in FIG. 3B).

35 Similarly to rotor 40, there is shown in FIG. 3B the rotor 24 on shaft 28 and having a hollow interior outlined by 24L_o. The hatched area on the right shows abutment 24_a while at the left is seen the piston 2_c interleaved between abutments 24_b and 24_c (not shown in FIG. 3B). Bearings 29_a and 33 hold the rotor 24 in place, and (similarly to rotor 40) cooling air may enter the interior of the abutment rotor 24.

40 The central rotor timing gear 8 intermeshes with gear 50 to rotor 40 and with gear 34 of rotor 24 to provide and continuous communication for purposes of timing cooperation and for distribution of power between the three rotors.

45 Continuous Combustion Engine Operation

Since a number of aspects of this embodiment have similarity to my U.S. Pat. No. 3,640,252, reference to the description of operation in that patent may be helpful toward understanding of this embodiment, and are included herein by reference.

50 Referring to FIG. 3A of this invention, combustion fluids are taken in through intake port 60 and compressed into central chamber area 38_c where rotation of rotor 2 deposits the compressed fluids into peripheral chamber 75. The turning rotor 24 entraps these fluids in the abutment cavity where further compression occurs as the piston 2_b enters the abutment cavity between abutments 24_b and 24_c after which the compressed fluids enter the combustion chamber area 68. 55 At this point, an ignition means such as sparkplug 69 ignites the fluids causing an expansion and heat generation which drives piston 2_b further clockwise and to the left. Since the rotors are linked by gears 8, 34, and 50 (of FIG. 3B), the rotary power also transfers to rotors 60 24 and 40.

65 No particular timing is required of the ignition means 69 in combustion chamber 68 since the burning is a

continuous burning rather than a pulsating burning. Channel 75_a carries or feeds back combusting fluids around in chamber 75 over to the area where fresh charge of compressed fluids is being brought in by rotor 2 and its pistons. Further, with rotation of rotor 24, combusting gases are recirculated around through channel 75_a for re-entry into the area where rotor 2 is depositing freshly compressed charge where an enturbulence is made causing the mixing of fresh charge with partially combusted charge to bring about a thorough burning which will most substantially reduce and eliminate the undesired and noxious emissions so characteristic of the prior art internal combustion engines.

Fuel injector 69_i is used to introduce fuel vapor into the charge moving through the channel 68_e.

The expanding gases or fluid from the combustion chamber 68 further drive the pistons of rotor 2 and are also carried through channel 38_e by the side faces of the piston abutments over to the exhaust port 72 where, due to rotation of rotor 40 (which carries fluids such as fresh air) the exhaust gases or fluids are mixed with fresh air for final burning and cooling as they are being discharged through exhaust port 72.

Similarly to my U.S. Pat. No. 3,640,252, the sealing of the function-chambers 38_c and 38_e is accomplished by the juxtaposition of the long head areas such as 2_h in proximity to the casing walls of the chamber 38. Likewise, the same is true for the rotor abutment heads 40_h and 24_h juxtaposed to their respective casing chamber walls.

Further in this embodiment, the interleaving between the pistons and abutment cavities follows the form described hereinbefore in the previous embodiments, and also later described in conjunction with FIGS. 4A and 4B.

The overall combustion process of this embodiment of the invention permits a constant pressure expansion of the intaken air of fluids coming through the intake port whereby the combustion chamber by-products are applied together with their generated heat to the intaken charge. The combusting by-products from the combustion chamber expand into the expansion chamber area (68_e and the upper area of 75) which is all times common with the continuous combustion chamber 68, and the expansion pervades into the cavities between the second rotor abutment at a relatively constant rate.

Neither the combustion chamber area 68 or the abutment rotor cavities of rotor 24 are exposed to the exhaust port 72 at any time so that the only means by which the products of combustion can escape is through channel portion 38_e at the end of the expansion phase of the piston rotor and after the next succeeding piston has blocked off the expansion channel 38_e from communication with the combustion chamber 68, as also was previously explained in my U.S. Pat. No. 3,640,252.

As each piston arrives in about the middle of the expansion channel 38_e, some of the combustion products are trapped in the cavity between adjacent rotor abutments and are carried around the abutment channel 75_a to be combined with fresh fluids or fresh air charge from the compressor function-channel 38_c at the same operating pressure as the combustion chamber 68 pressure. This constitutes a most important improvement factor since it provides the means for conserving large amounts of heat and conserves the working media with-

out the expenditure of any extra work during the process.

The valving abutment rotor 24 performs a function similar to that of the "displacer piston" in the Sterling Hot-Air Engine. The recycling of hot combustion products back into the fresh air stream from the piston compressor of the main rotor 2, therefore, constitutes a closed cycle heat-regenerating process within the overall combustion process. Further, this closed cycle provides for the conservation of large portions of the combustion products that are useful as working media for further expansion, and also as damping media to control the maximum temperature of the combustion process for the reduction of nitrous oxide emissions.

15 The recycled heat not only provides energy for expansion but also preheats the incoming charge for improved vaporization within the combustion chamber 68.

The output of the compressor portion of the rotor 20 piston 2 at the upper end of chamber 75 provides a pulsating pressure since the compression is essentially an adiabatic process, but the channel 68, which communicates between the combustion chamber 68 and the piston compressor output at the top area of chamber 75, 25 is relatively long and considerably larger in volume than the charge carried in a single impulse of compressed air from the compressor function of the rotor 2; therefore the working pressure at the inlet to the combustion chamber 68 remains relatively constant.

30 The building up of working pressure in the channel 68_e and in the combustion chamber 68 is entirely the result of the combustion process, since the volume of the channel 38_e (utilizer) is the same as the volume of the channel 38_c of the piston compressor.

35 At cranking speeds, in starting, and before combustion has begun, there is no buildup of working pressure. The pressure is only built up after, and by virtue of, the commencement of the combustion process since the working medium is thereby expanded and can only escape through each successive passing of the piston past the exhaust port after the combination chamber 68 has been blocked off from communication with the channel area 38_e.

40 Engines of the prior art, such as the Breele U.S. Pat. No. 2,927,560, allow the combustion chamber and the abutment cavity or well to be scavenged and thereby make it impossible to build up a high working pressure or to allow the entrapped heat combustion products to be utilized for regenerative and damping purposes. This 45 very unique feature of my invention is especially and significantly useful in improving the purity of the exhaust emissions, besides improving efficiency.

45 A further improvement, also provided in my U.S. Pat. No. 3,640,252, is the means for entrapping fresh air between the abutment cavities of the first peripheral rotor 40 (exhaust abutment rotor) whereby fresh air is carried around the inner channel of chamber 76 and into the exhaust port 72. The present invention and embodiment is further improved in that the intake port 60 is now common to both the abutment rotor 40 and piston rotor 2, and no auxiliary intake port is needed for displacing air into the exhaust port 72.

50 It is also of significance to point out that while the standard reciprocating piston-cylinder type engine requires a bidirectional set of two opposite motions, the above described embodiment is unidirectional in the sense that the piston rotor goes continuously in only

one direction, thus allowing for a smooth continuous flow of power without excessive vibration or need for balancing. It should also be pointed out that the embodiment of FIG. 3A minimizes the problem of sealing since the cooperation of the casing walls with the rotor abutments and the pistons together with the unique configuration of the interleaving elements, lays to rest once and for all, the prior art problem of sealing of cavities and function-chambers which move in a rapid fashion.

The use of a durable heat-insulating material, such as a ceramic, for construction of the rotors and engine casing with its continuous combustion chamber can provide further advantages in conservation of heat by eliminating the loss of heat in the cooling of engine parts and by allowing the inner surface of the combustion chamber and the channel 38, to operate at a higher temperature for more efficient combustion of fuel.

No throttling of this engine embodiment is necessary or desirable since the operating temperature of the combustion process is lower for a given load if a maximum flow of air is allowed. Any excess air in the combustion chamber 68 serves as a directly heated working medium and allows the fuel/air mixture to remain very lean under normal to light loading. The maximum richness of fuel/air mixture under heavy loading is conveniently limited by limiting the relative fuel flow as such by use, for example, of a positive displacement fuel injection pump which is driven from the engine shaft. Throttling of the engine is preferably done by means of a variable relief system for controlling the fuel injection pressure.

The ignition means 69, such as a spark plug, in the combustion chamber 68 is mainly used for starting, but is also preferably fired either continuously or at an arbitrary rate to insure that the combustion process is not interrupted by temporary loss of fuel injection pressure as would occur during deceleration.

Piston and Abutment Geometry

The following discussion is done in gradual portions so that it is necessary to read the entire section before a complete understanding of the principles involved is fully comprehended.

In regard to the interleaving and cooperative arrangement of the peripheral rotor abutments (and peripheral rotor cavities) with the piston-abutments (and piston-rotor cavities), I have discovered a unique and critical configuration which provides an optimum geometrical relationship.

As previously described, the side faces of the pistons form arcs having or following a circle whose center has been designated as M. Similarly, the concave side faces of the peripheral valving rotor abutments are arcs which follow a curve of a circle having a center designated C (C_1 and C_2). This configuration is a substantial improvement over any of the prior art forms of interleaving rotating abutment type energy converters, including that of my U.S. Pat. No. 3,460,252.

In the present invention, both of the convexly arcuate side faces of the pistons are formed by opposite sides of a single circle. Subsequently thus, the arcuate faces of the peripheral abutments are very simply derived from the passage of the "piston circle" between the cavity formed by the side faces of the two adjacent abutments of each peripheral rotor.

By using the peripheral abutment rotor (as described above) as a stationary reference frame, I have found that the motion of the center point M of the "piston circle" describes a prolate epicycloidal path relative to the abutment rotor whereby and in which the central rotor timing gear (element 8 of FIG. 3B) pitch lines are the rolling circles involved in the generation of the prolate epicycloidal curve shown as M, M' and M'' in FIG. 4A.

10 An epicycloidal curve is that curve described by a point (P) on the circumference of a "rolling" circle (of radius a) which rolls along the outside circumference of a fixed circle (of radius b). When the generating point (P) is beyond radius (a), then the curve of point 15 P is called a "prolate" epicycloidal curve.

In the present invention, the epicycloidal curve is deemed "prolate" because the center of the "piston-circle" M (or the generating point), is beyond the pitch circle (8p) of the gear 8. This pitch circle of the gears 20 (which can be called the rolling circle) may be larger or smaller in radius than the fixed circle.

It should be noted from FIG. 3B that the timing gears 25 50, 8, are of unequal pitch diameter. However, since the center point M of the "piston circle" is slightly beyond the pitch circle this factor makes the generating point beyond the rolling circle bringing about the "prolate" characteristic wherein the generating point is beyond the rolling circle a, shown in FIG. 4A.

The ideal shape of the abutment side faces is therefore essentially epicycloidal since the entire "piston circle" operates as an enlarged generating point. As will be seen in FIG. 4A with reference to the peripheral rotor abutments, the sharp junction of the abutment head line (40_h) with the abutment side face line (40L and 40_t) is rounded off so as to provide extra clearance for the piston side faces as they follow their epicycloidal line into the cavity of the peripheral rotor. Thus the outside corners of the peripheral abutments are removed to eliminate any interference problem and allow greater machining tolerance to the piston-abutments.

Since a liberal clearance is allowed between the piston faces and the peripheral rotor abutment faces and corners, it is not necessary to form the abutment faces of the peripheral rotor precisely according to the ideal epicycloidal curves. However, since these curves are very nearly circular, it will be adequate to make a circular approximation of the involved sections of the prolate epicycloidal curves.

Thus, the main curve of the abutment side faces are 50 established with a circular curve that is of approximate radius to and so juxtaposed to the ideal curve so as to have all of the ideal curve within the circular approximation, as will be later seen in FIG. 4A.

Likewise, the cut-off outside corners of the peripheral rotor abutments constitute a circular approximation and are of appropriate radius and juxtaposition so that the corner circular approximation is entirely within the ideal curve.

In order to provide a uniform clearance between the piston faces and the peripheral rotor abutment faces, the actual piston circle radius is made slightly smaller (in the amount of approximately 2 to 5 percent) than the ideal piston circle used to generate the ideal prolate epicycloidal curves of the abutment faces and corners.

60 65 The above-described means for interleaving of piston and abutments is extremely versatile such that variations of the major and minor piston radii and major and

minor peripheral rotor abutment radii are exceptionally useful in adapting these rotors to embodiments of both lobe-type rotors and carrier-disc type rotors where one or both ends of each piston or abutment is supported by a rotary disc having pistons or abutments protruding from one of or both faces thereof.

The above mentioned versatility of my invention including this rotating abutment means also allows for variability in dimensional relationships for optimization of any given rotary energy converter design without altering the basic discovery and formula by which the abutment curves are derived from the piston circle. Thus the needed freedom of design is provided for the many and varied applications of the invention.

Referring to FIG. 4A, there will be seen an enlarged and partial view of a peripheral rotor abutment and cavity shown for example, as abutments 40_b and 40_c with the peripheral rotor cavity therebetween the side faces $40L$ and 40_t . The center of the peripheral rotor shaft is shown as 47_c . The hub of the peripheral rotor is shown at 40_u which is part of the hub circle designated as 40_{uc} .

By side reference to FIG. 3B, it will be seen that the rotor 40 has a timing gear 50 having a gear pitch-line circle labelled 50_p . Now referring to FIG. 4A, the pitch line circle 50_p is shown as a reference circle or "fixed" circle for geometrical purposes whereby it will be used as a reference about which a "rolling circle" 8_p will be rolled about the "fixed" circle, 50_p , as will be explained hereinafter.

The circle 8_p or rolling circle represents the gear pitch line 8_p of gear 8 also shown in FIG. 3B. The previously described point M of FIG. 3B (as the center of the piston circles) will, during rotation of the piston rotor form a circle shown as M_r . The point M is the center of the piston circle marked C_M with projected motions labelled $C_{M1}, C_{M2}, C_{M3}, C_{M4}, C_{M5}, C_{M6}, C_{M7}$, and C_{M8} . The center point M is shown describing the curve $M-M'-M''$ of a prolate epicycloid. The point C_c is used as the actual center of a circle whose circumference traces the abutment side faces.

Now, for analytical and geometrical purposes, by taking the peripheral abutment rotor 40 and its pitch line circle 50_p as a stationary unmoving reference and then taking the piston circle C_M with its center point M and with its timing gear pitch-line 8_p as a rolling circle which is rolled around the fixed circle 50_p , it will be seen that the center point M of the piston circle traces a curve designated $M-M'-M''$ forming a prolate epicycloidal form. Since the center point M traces this form, then also the circumference (of the piston circle) C_M will also trace the path of a prolate epicycloid as seen in the series of circle labelled C_{M1} through C_{M6} which optimumly juxtapose into the cavity between the peripheral rotor abutment side faces $40L$ and 40_t .

As the piston rotor 2 is (analytically and geometrically) moved about the stationary reference of the peripheral rotor 40 , the circle designated $LC12$ is generated (as shown on FIG. 4A) by the center point of the piston rotor shaft 12 .

Piston circles C_{M7} and C_{M8} show theoretically how the piston circles juxtapose into the abutment cavity (from C_{M1} through C_{M6}) but since the hub circle 40_{uc} intrudes into the abutment cavity, the actual piston 2_a is made truncated at the line circle C_{M6} . This can also be observed in FIG. 3A where the piston has a truncated head area 2_h . The dotted line 2_{ad} shows how the piston

circle eventually juxtaposes between the side faces of the abutments 40_b and 40_c while at the same time the truncated head 2_h of the piston avoids actual physical contact with the hub circle 40_{uc} .

5 The head 40_h of the peripheral abutment rotor 40_b is made to have rounded off edges where the head line 40_h meets the side faces $40L$ and 40_t in order to allow greater tolerance in the machining of the pistons and the peripheral rotor abutments.

10 Referring to FIG. 4B, there is shown further how versatile the interleaving arrangements may be accomplished. A diagrammatic sketch is shown of the piston rotor 2 having piston 2_a and 2_d which interleave with a typical peripheral rotor abutment 40_b having a head area 40_h and its leading face $40L$ and trailing face 40_t .

15 As shown, the side faces of the piston 2_d follow the arcs of a circle having its center at point M . However, it should be noted that the side faces $2L$ and 2_t , which are centered on the point M , may be centered on a larger circle than the standard piston circle so that the side faces of the piston may be made to follow the curves $2L_c$ and $2L_t$ as shown in FIG. 4B. In this event, it is not even necessary to round off the abutment rotor corners as was described in the discussions of FIG. 4A.

25 **CONTINUOUS COMBUSTION ENGINE WITH RAM INTAKE DESCRIPTION**

30 A simple and inexpensive engine using specialized interleaving elements is shown in FIG. 5A. It may be described as a continuous combustion engine with ram intake and a stationary exhaust abutment. Only two moving rotors are required.

35 The engine is enclosed by a casing 20 having an opening or air intake 60 , wherein air passes through a channel 60_c past wall 60_w and 20_b to the area 60_d .

A main rotor 2 has four lobes or abutments $2_a, 2_b, 2_c$, and 2_d and wherein abutment side-face has a center point M .

40 The rotor 2 rotates in a chamber 38 to form function-chambers 38_c and 38_e for compression and expansion respectively. The rotor 2 is mounted on central shaft 12 which is fixedly attached to a timing gear 8 (as shown in FIG. 3B).

45 Interleaving with the main rotor 2 is a peripheral valving compression rotor 24 which rotates on shaft 28 and in a peripheral chamber 75 . The rotor 24 has three abutments $24_a, 24_b$, and 24_c each of which has concave side faces which are centered on a point marked C_1 . The peripheral rotor 24 has a central shaft 28 which is fixedly attached to a timing gear similar to that shown at 34 of FIG. 3B.

50 Communicating with chamber 75 is a duct 68_g which is scooped into the top or bottom of the chamber 75 and which passes cool intake air above and below the peripheral rotor lobe-abutments $24_a, 24_b$, and 24_c to provide cooling.

55 A channel 75_a is provided on one side of chamber 75 for cool air to pass along the skirt of a lobe abutment as $24b$ into a function-chamber 75_b , where hot combustion gases are mixed with cool intake air, which mixed gases then pass through passage 75_c into accumulator chamber 75_d , then through passage 68_f , into the combustion chamber 68 .

60 At one end of the combustion chamber 68 is a fuel-injector igniter 69 which will be described in connection with FIG. 5B.

A wall 68_w forms one side of the combustion chamber 68 while the wall 75_w forms one portion of the peripheral chamber 75. The wall 38_w is a barrier forming part of the central chamber 38. The wall 38_w forms one side of the central chamber 38 and the expansion function-chamber 38_e.

An exhaust port 72_r provides for exit of exhaust gases expelled from function-chamber 38_e.

FIG. 5B shows one form of igniter-fuel injector suitable for use as the element 69 of FIG. 5A.

The fuel injector igniter 69 is seen as composed of two elements which are inserted through the upper and lower walls of the combustion chamber. The first element is a spark plug 69_p which connects to a spark coil 90 to ground. The second element is a fuel injector 69_f, also connected to ground and whose nozzle, 69_n, is spaced in proximity to the end of the spark plug so that ignitive sparking occurs from the spark plug over to the metallic casing supporting the nozzle. Thus injection of fuel into the cavity of the combustion chamber is accomplished by the fuel jet striking the end of the spark electrode and being deflected radially in all directions perpendicular to the fuel jet. Fuel vaporization is aided by the spark and the ignition of fuel is also accomplished.

OPERATION

With reference to the above description of FIGS. 5A and 5B, fresh air is intaken through port 60_r and passes down the long channel or ram 60_r where it is compressed in function-chamber 38_c by a piston abutment lobe such as 2_a and passed to the common chamber area 61. The counterclockwise motion of valving rotor 24 carries a portion of the fresh air into function-chamber 75_m where a portion of it is pushed into combustion chamber 68.

Another portion of the intaken compressed air passes over and under peripheral the abutment lobe such as 24_b into function-chamber 75_b through duct 68_g and passage 75_a where it mixes with hot gases being recirculated by rotor 24. These mixed gases then pass through passage 75_c to accumulator chamber 75_d, thence through passage 68_f over in to the combustion chamber 68.

At this point the fuel injector-igniter 69 provides fuel injection and ignition to cause continuous combustion to drive a piston abutment such as lobe 2_c in a clockwise direction where the burned gases exhaust through port 72_r.

The turbulent mixing of hot gases with cool compressed air, which takes place in function-chamber 75_b and in the combustion chamber 68, provides a "damping" and cooling effect which dilutes the oxygen present with CO₂ and CO and H₂O. This damping effect, by thus diluting the quantity of pure oxygen present has a significant effect in eliminating the production of the undesirable nitrous oxide (NO_x) emissions presently characteristic of reciprocating piston engines of the presently-used type, which flash and produce high compression to form the proper situation for production of (NO_x). My engine is instrumental in keeping down the compression and temperature so that the required conditions for (NO_x) production do not occur in the engine operating cycle.

The embodiment of FIG. 5 utilizes high pressure air from the compression of the rotors to cool the peripheral rotor 24 by permitting air to flow around the pe-

riphery of the abutments. The compressed air then combines with burned gases after which it flows to provide some cooling for the combustion chamber along wall 68_w and for the main chamber along wall 38_w.

5 The main piston rotor 2 is cooled by its exposure to incoming cool air from the ram passage 60_r. The ram air intake also provides a more constant flow of air into the intake air 60_d than a simple intake port, since the kinetic energy of incoming air continues to flow around the lower portion of rotor 2 even when the compression function-chamber 38_c is temporarily sealed during the rotary cycle.

CONTINUOUS COMBUSTION ENGINE WITH HIGH PRESSURE COOLING

15 The rotary converter shown in FIG. 6 is an embodiment wherein hollow rotors are used (as illustrated in FIG. 3B).

An engine casing 20 is arranged to provide a central chamber 38 and first and second peripheral chambers 76 and 75 having peripheral valving rotors 40 and 24. Other elements are numbered as in the description of FIGS. 3A and 3B, except for the added and distinctive features to be described hereinbelow in connection with FIG. 6.

20 Referring to FIG. 6: connecting the intake port 60 with the first peripheral chamber 76 is a duct 82 which permits cool intake air to pass into the internal hollow spaces (see FIG. 3B) of rotor 40 so as to exit at the top of rotor 40 and into another duct 83 where the fresh intaken air can be carried by the abutments of rotor 40 into the exhaust port area 72 for burning and cooling of exhaust gases being forced out from expansion function-chamber 38_e. Offset chambers 83_a (adjacent the first peripheral chamber), 80 (adjacent the second peripheral chamber), and 68_g (adjacent the second peripheral chamber) are also provided.

25 The second peripheral chamber 75 has an offset chamber 80 which connects to an under duct 80_a under, but not common with peripheral chamber 75. Duct 80_a connects with another duct 80_b which carries fluids from 80_a to the bottom of main rotor 2, and to the bottom of rotor 24 and up through its hollow internal areas to exit at the top into a duct 80_c where the fluids are carried to upper duct 80_d which is above but not common with chamber 75 and into the second offset chamber 68_g after which gases can pass through passages 68_{g1} and 68_{f1} into the combustion chamber 68. A fuel-injector-ignitor 69 as previously described, is provided 30 in combustion chamber 68.

OPERATION

35 The operation of this embodiment of FIG. 6 follows the basic operation of that described in FIGS. 3A and 3B but with the addition of the high pressure cooling features and the more optimal use of internally generated heat.

40 The cool intaken air entering port 60 can pass through lower duct 82 through the hollows of rotor 40 to cool rotor 40 and pass through upper duct 83 into an offset chamber 83_a to enable rotor 40 to bring fresh cooling air into mixture with the exhaust gas at exhaust port 72 to burn further any unburned exhaust gas in addition to cooling the exhaust gases.

45 The compressed intaken air in function-chamber 38_c is fed into the second peripheral chamber 75 and into offset chamber 80 and then to the lower duct 80_a. It

then passes to connecting lower duct 80_b over to the lower end of the main rotor 2 and rotor 24; then passes internally through rotors 2 and 24 and out into upper duct 80_c. It then passes along the upper casing over to the top of rotor 24 through duct 80_d to offset chamber 68_a and thence along the long passage 68_{ra}, passage 68_{ra} to combustion chamber 68.

It should be noted that the cooling action through the ducts and rotor hollow spaces is of a high pressure level since it occurs basically from the compression phase of the main rotor pressing cool air through ducts 80_a, 80_b, 80_c, and 80_d. Further the cooling action of ducts 82 and 83 through the exhaust valving rotor 40 is pressurized by the counterclockwise action of exhaust rotor 40 into the exhaust port area 72. This motion of the exhaust rotor 40 also creates a vacuum action at intake port 60 to pull in fresh air.

The first offset chamber 80 (adjacent chamber 75) brings together compressed cool air with combustion gases from combustion chamber 68 due to counterclockwise motion of the valving rotor 24. This mixture circulates through rotors 2 and 24 to cool the rotors and at the same time picks up heat to be later used in the second offset chamber 68_a to feed back to the combustion chamber 68. This flow through passage 68_{ra} cools the lower wall 68_w of combustion chamber 68 and insulates it from the lower outer wall of the casing while still permitting the heat of the fluid flow to be reintroduced into the combustion chamber. Thus the overall effect is to take heat that would be normally wasted, in order to make further use of it, while simultaneously using it for cooling since it is lower in temperature than the combustion chamber. This is deemed to be of significance in terms of efficiency since, in standard reciprocating piston engines, 30 percent or more of heat generated is completely lost and must actually be removed.

The embodiment of FIG. 6 may also be regarded as a heat displacer which transfers heat from undesirable areas to be useful in more desirable areas.

CONTINUOUS COMBUSTION ENGINE WITH THERMAL REACTOR

DESCRIPTION

As seen with reference to FIG. 7, there is shown distinctive an embodiment of a continuous combustion engine with an internal form of "thermal reactor." A casing 20 encloses three rotors comprising a central rotor 2, and first and second peripheral rotors 40 and 24. This embodiment basically follows those embodiments shown in FIGS. 3A, 3B, and FIG. 6 with the corresponding elements numbered the same, except for additional and distinctive elements which will be described herein.

An intake port 60 carries air into a long channel 60_c to the intake area 60_d. The compression function-chamber 38_c carries a portion of the compressed cool intaken air into a first offset chamber 80 which connects to a lower duct 80_a forming a passage to the bottom end of rotor 2 and also the bottom of both valving rotors 40 and 24. The conducted air then can pass upward through the internal hollows of rotors 2 and 40 and 24 to the top of these rotors and then into upper duct 80_b. Upper duct 80_b connects to upper duct 80_c which carries cooling air over to offset chamber 68_a which communicates with combustion chamber 68 through passage 68_{ra}. A long exhaust chamber 72_e is

provided with a throat 72_a, passage 72_b and exhaust port 72. A wall 68_w separates the combustion chamber 68 from the exhaust passage 72_e. A wall 38_w helps to form one portion of the central chamber 38.

Two small rods, 69_x and 69_y, of material such as tungsten carbide are provided near injector-igniter 69 to create turbulence for improved air-fuel mixing.

OPERATION

Referring to FIG. 7, intake air enters through port 60 through passage 60_c to area 60_d. A portion of the intaken air is scooped by rotor 40 into the exhaust chamber throat 72_a to mix with ejected exhaust gas from rotor 2 to provide more complete burning of exhaust gas and subsequent cooling.

The major portion of intaken air at area 60_d is compressed by rotor 2 in function-chamber 38_c and taken into combustion chamber 68 to feed the continuous combustion process which will drive the piston abutment-lobes of rotor 2.

Valving rotor 24 drives some of the combusting gases around into offset chamber 80 for mixing with the compressed intaken fresh air, which mixture is partially circulated through ducts 80_a, 80_b, and 80_c providing a cooling action due to the circulation through the internal hollows of rotors 40, 2 and 24, to be returned back into combustion chamber 68. Thus heat derived from the rotors is returned to enhance the combustion in chamber 68 while having also served a cooling function in the internal rotors.

Exhaust gases pushed by rotor 2 into throat 72_a then mix with cool air as previously described to cool wall 68_w of combustion chamber 68. The long passage and gradual cooling through exhaust passage 72_b helps prevent the sudden temperature changes which tend to produce NO_x emissions in ordinary engines. The long exhaust channel is also helpful in providing more complete burning of the exhaust gases then would normally occur.

In this embodiment, all three rotors are cooled by the mixture of cool high pressure air and recycled gases. This mixture is further used to cool wall 38_w of central chamber 38.

Since this engine operates primarily as a constant pressure type engine, then when the exhaust gases are pushed into exhaust channels 72_a and 72_b, the pressure drop is very great. Thus, and assuming complete combustion has occurred, the exhaust gas will cool very rapidly with the pressure drop, and this cooled-down exhaust gas can be used to further cool the wall 68_w of combustion chamber 68. But since the wall 68_w passes heat to the exhaust gases, the cooling effect on the exhaust is given a time delay which further prevents occurrence of the standard conditions which make for NO_x production.

Further, this embodiment has a "thermal reactor" effect in that it tends to keep the engine at an even temperature due to the very long paths of circulation of the mixed gases.

CLOSED CYCLE EXTERNAL COMBUSTION ENGINE

DESCRIPTION

An embodiment of the invention which may be called a closed cycle external combustion engine is shown in FIG. 8. This unit has an internal sealed section containing a high heat latency fluid such as Argon which is iso-

lated from an external section where the heat is generated.

The external heat generation section takes in air at port 60 through a pre-heater passage 60_c and around to a combustion chamber 68 containing a fuel-injector-igniter 69. Generated heat then passes through a long passage 72_b to the exhaust port 72.

An overall casing 20 has cooling fins 21 on the cooling side of the sealed section; and sealed within the casing 20 are the main rotor 2, and first and second peripheral rotors 40 and 24. The previously described basic configuration of FIGS. 3A and 3B is followed with three internal chambers, with the central chamber 38 and first and second peripheral chambers 76 and 75. A first offset chamber 80 connects to a lower duct 80_a which carries fluids over to a second offset chamber 68_a which communicates with a heated area 68_b.

OPERATION

Fresh air is intaken through port 60 and carried to combustion chamber 68 where fuel injector-igniter 69 causes combustion and heat to be generated through passage 72_b.

The heat in passage 72_b heats wall 68_w causing the internal fluid, such as Argon, in area 68_b to heat up and expand. This expansion creates a pressure on the piston abutment lobe of rotor 2 turning it clockwise. Since rotor 2 is connected through timing gears (as seen in FIG. 3B) to rotors 40 and 24, they will also turn. Thus, hot internal fluid will be circulated by rotor 24 into offset chamber 80 where it mixes with cooler fluid as Argon coming from function-chamber 38_c of rotor 2. The mixed fluids in offset chamber 80 are pushed through lower duct 80_a over to chamber 68_a for re-entry into area 68_b for further heat pickup.

The heated internal fluids in expansion function-chamber 38_e are pressed into chamber area 62 where they circulate through passage 62_a adjacent cooling fins 21 for cooling of the Argon fluid, after which they enter the compression function-chamber 38_c of rotor 2 for mixture with the hot fluid or Argon entering offset chamber 80.

The circulation of the hot exhaust fluid, such as Argon, around the cooling area of fins 21 is expedited by the rotary action of exhaust valving rotor 40, (on shaft 47) which helps propel the hot exhaust fluid, as Argon, into passage 62_a.

The application of external heat at 68_b to the sealed Argon with the consequential motive pressure on the rotors provides mechanical power generation. This power generation is regulated according to the heat generated in chamber 68 and can be controlled by regulation of the fuel injector-igniter 69 depending on the amount of power desired to be generated. The output power take-off may be obtained from the shaft 12 (of rotor 2) through its outward extension 12_a as seen in FIG. 3B.

The expansion of the working medium (sealed fluid) due to the external heating drives the engine at constant pressure which is built up by the second peripheral valving rotor 24 (on shaft 28) working against the expanding gases in the combustion chamber 68. When the expanding fluids in heat chamber area 68_b pass through expansion function-chamber 38_e into the area 62, the fluids cool rapidly because of the sudden pressure drop. The external cooling means, shown as fins 21, further cool the exhaust fluids as they pass through

passage 62_a, which is the low pressure or cold side of the engine. Portions of the cooled fluids are drawn into compression function-chamber 38_c and other portions are drawn by exhaust peripheral valving rotor 40 back into area 62 for further cooling circulation.

The second peripheral rotor 24 also recycles heat from the heat chamber area 68_b into offset chamber 80 and back into the heat chamber area 68_b so that the heat of the recycled fluid is used again to contribute to the expansion process. This is similar in principle to the action of the displacer piston and the fine-mesh used in the Sterling hot air engine. However, my embodiment does not require the fine metallic mesh of Sterling since the hot expanding fluids are mixed with the compressed cool fluids for heat recycling in the expansion process.

With the foregoing specification, I have described my invention for Rotary Converters having specialized interleaving elements together with various embodiments showing how my invention has broad and general applicability to a wide variety of apparatus and equipment serving a variety of purposes. I thus make the following claims.

What is claimed is:

1. An engine powered from an external energy source comprising:
  - a. a casing forming a sealed cavity and forming internally a central chamber and first and second peripheral chambers;
  - b. a central rotor in said central chamber and first and second peripheral rotors in said first and second peripheral chambers, each of said rotors having a hub with extending protrusions;
  - c. connection means for timing said central rotor in an interleaving relationship with said first and second peripheral rotors during the rotary cycle;
  - d. a high heat latency fluid for storage in said sealed cavity;
  - e. a heat-receiving chamber communicating with said central and said second peripheral chambers;
  - f. means for application of heat energy to said heat-receiving chamber;
  - g. means for heat removal from said first peripheral chamber.
2. The engine of claim 1 including:
  - h. an offset chamber communicating with said second peripheral chamber;
  - i. passage means connecting said offset chamber to said heat-receiving chamber.
3. An engine powered from an external energy source comprising:
  - a. a casing forming a sealed cavity and forming, internally within said cavity, a central chamber and first and second peripheral chambers;
  - b. a central rotor in said central chamber and first and second peripheral rotors in said first and second peripheral chambers, each of said rotors having a hub with extending protrusions;
  - c. connection means for moving the protrusions of said central rotor in timed interleaving relationship with the space gaps formed by the protrusions of said first and second peripheral rotors during the rotary cycle;
  - d. a high heat latency fluid for storage in said sealed cavity;
  - e. a heat-receiving chamber communicating with said central and said second peripheral chambers;

f. means for application of heat energy to said heat-receiving chamber;
 g. means for heat removal from said first peripheral chamber;
 and wherein the protrusions of said central rotor have side faces which are convexly arcuate and which follow the arc of a circle having a center within the protrusion body; and
 wherein the protrusions of said peripheral rotors have concave side faces forming space gaps which follow the arc of a circle whose center is outside of the body of the protrusion; and
 wherein the center point of the circle for the side faces of the central rotor protrusions describes the path of a prolate epicycloid with respect to the peripheral rotor when said peripheral rotor is regarded as a stationary reference about which the central rotor is revolved.

10

15

4. The system of claim 3 including:
 h. an offset chamber communicating with said second peripheral chamber;
 i. passage means connecting said offset chamber to said heat-receiving chamber;
 j. means for circulating heated internal fluids in proximity to said means for heat removal.

5. The system of claim 4 wherein:

said means for application of heat energy includes a preheater passage for passing incoming fluids in proximity to a heated portion of the casing.

6. The system of claim 4 wherein:

said means for application of heat energy includes an external combustion chamber and fuel-injector igniter for providing heat in proximity to said heat-receiving chamber.
